[57] CLAIM

The ornamental design for a heel notch for a golf club head, as shown and described.

DESCRIPTION

FIG. 1 is a front elevational view of a heel notch for a golf club head showing one embodiment of our new design; FIG. 2 is an end view of the heel notch shown in FIG. 1; FIG. 3 is a rear elevational view of the heel notch shown in FIG. 1; and, FIG. 4 is a bottom view of the heel notch shown in FIG. 1. The broken lines in FIGS. 1-5 are for illustrative purposes only and form no part of the claimed design.
